UNITED STATES PATENT OFFICE.

JOSEPH R. BLAINE AND CARL HENDERSON, OF CHICAGO, ILLINOIS, ASSIGNEES TO
MIEHLE PRINTING PRESS & MANUFACTURING COMPANY, OF CHICAGO, ILLINOIS,
A CORPORATION OF ILLINOIS.

PRELIMINARY SIDE-REGISTER MEANS.

Application filed February 1, 1922. Serial No. 533,375.

To all whom it may concern:

Be it known that we, JOSEPH R. BLAINE and CARL HENDERSON, citizens of the United States, residing at Chicago, in the county of Cook and State of Illinois, have jointly invented certain new and useful Improvements in Preliminary Side-Register Means, of which the following is a specification.

This invention relates to printing presses and more particularly to preliminary side register means.

In printing presses, and particularly those provided with automatic feeding devices, the sheets are conveyed a certain distance from the feeding pile to the printing cylinders. It is difficult, if not impossible, to so arrange the sheets in the feeding pile that each one thereof will be delivered to the transfer or conveying mechanism at exactly the same point. Therefore, it is necessary that means be provided for not only guiding the paper in its travel, but for shifting the same laterally if necessary to bring it into proper relation with the registering mechanism at substantially the point of engagement with the cylinder. The main registering mechanism will act to properly position a sheet if it is only a small amount out of register, but if received more than one-half inch out of register, for example, it will not register it properly.

One object of the present invention is to provide simple, reliable and efficient preliminary side register means whereby the successive sheets of fed paper may be presented to the main registering means practically in side register position.

Another object is to provide improved side register mechanism in which the various parts cooperate in a manner for successful commercial operation.

These and other objects are accomplished by means of the arrangement disclosed on the accompanying sheet of drawings, in which—

Figure 1 is a fragmentary side elevation of a printing press embodying the invention;

Figure 2 is a fragmentary top plan view of the same;

Figure 3 is an enlarged detail view showing a part of the side register control mechanism;

Figure 4 is a detail enlarged view of the same arrangement shown in Figure 3, but at an angle of 90° with respect thereto;

Figure 5 is an enlarged detail view of another part of the preliminary side register means;

Figure 6 is a view of the same arrangement shown in Figure 5, but at an angle of 90° with respect thereto;

Figure 7 is a diagram showing circuit connections for controlling the extent of side register movement of the sheets of paper; and, Figure 8 is a detail top plan view of a second actuating connection for the side register means.

The various novel features of the invention will be apparent from the following description and drawings and will be particularly pointed out in the appended claims.

Referring to the figures of the drawings, it will be noted that we have disclosed our invention in connection with a printing press having side frame members 11, between which sheet feeding rollers 12 are mounted for conveying sheets from the preliminary side register means to the main front and side register means indicated generally at 13. The sheets are fed toward the preliminary side register means on tapes 14, which pass around a roll 15.

Mounted on the frame members 11 are two bearing brackets 16 in which a shaft 17 is rotatably oscillated and also endwise movable. Secured to the shaft 17 are two arms 18, in the outer ends of which is mounted a shaft 19 carrying two drop rolls 20. Mounted on the shaft 19 is a gear 21 meshing with a suitably supported intermediate gear 22 in turn meshing with a gear 23 loosely mounted on shaft 17, which gear 23 in turn may be driven from a gear on one of the rollers 12. The drop rolls 20 are driven in a counterclockwise direction, as viewed in Figure 1, for the purpose of assisting in the progressive feeding of paper which is fed between the rolls 20 and under feed rolls 12. The drop rolls 20 are raised preparatory to receiving a sheet of paper by the action of a cam 24 mounted on a shaft 25, a roller 26 mounted in one arm 27 of a bell crank lever 28 cooperating with said cam. The bell crank lever 28 is pivoted at 29 and has a second arm 30 to which

one end of a link 31 is pivoted, the other end being pivotally connected to one end of an arm 32 fixed to the shaft 17. It is seen, therefore, that as the cam 24 is rotated, the drop rolls are given an up and down movement, the upward movement of the drop rolls 20 permitting the release of said sheet at the time that it passes into operative association with the main register mechanism 13.

As soon as a sheet of paper is received between and engaged by the drop rolls 20 and the associated under rolls 12, the sheet is given a sidewise or lateral movement for a preliminary side register of the sheet. This lateral movement is effected through a second cam 33 mounted on shaft 25 and properly timed with respect to the associated cam 24 to function in the proper sequence. Cooperating with the cam 33 is a roller 34 mounted in one arm 35 of a bell crank lever 36 pivoted at 37 and having a second arm 38 to which one end of a link 39 is pivoted, the other end of said link being operatively connected to one arm 40 of a T-shaped lever pivoted at the upper end of its stem, as at 41. The stem or second arm 42 of the T-shaped lever carries a roller 43, which is located between two shoulders of a collar member 44 fixed to the shaft 17. It is apparent, therefore, that as the bell crank lever 36 is given a clockwise movement, as viewed in Figure 1, by its roller 34 rising on the cam 33, the shaft 17 is given a lateral movement. As shown in Figure 2 of the drawings, this lateral movement will be toward the far side of a second press, but it will be understood that if the connecting rigging including bell crank 36 and a link 39 is connected to the other arm 45 of the T-shaped lever, as shown in Fig. 8, the shaft will be moved toward the near side of the press. As shown in Figure 2, however, sheets are to be registered toward the far side of the press.

Some sheets when fed to the preliminary side register means are farther out of side register than others. Accordingly, the endwise throw of the shaft 17 laterally of the press should be sufficient to accommodate the sheet out of side register a maximum amount. To accomplish its purpose, the shaft 17 must stop its lateral movement instantly when the edge of the sheet is in proper side position. Accordingly, means have been provided to limit movement of the shaft 17 toward the side of the press in accordance with side register conditions, any excess in the throw caused by the cam 33 being absorbed by a spring 46 coiled around link 39 and interposed between a nut 47 on said link and an abutment 48 on the T-shaped lever in which one end of the link 39 is slidably mounted.

In connection with the lateral movement

of the sheet, the shaft 17 is provided with a rack member 49 having oppositely directed teeth at its opposite ends and which permits rotary oscillatory movement of the shaft 17 without a corresponding movement of the rack, the latter being mounted on top of the shaft 17 in a slot 50 in one of the brackets 16. The rack member 49 is fixed on the shaft 17, in so far as endwise movement is concerned, by engaging the collar member 44 on one end and at the other end engaging another collar 51 fixed to the shaft 17. Cooperating with the rack is a pawl 52 pivotally mounted at 53 in the bracket 16, one end of the pawl 52 being operatively connected at 54 to a movable core 55 mounted in a magnet or solenoid winding 56 so that when the solenoid is energized, the operative end of the pawl 52, against the tension of a spring 57, is forced into operative engagement with the rack 49 for preventing further endwise movement of the shaft 17 in the direction in which it was traveling, thereby preventing further lateral movement of the sheet being handled for side registering. The energization of the solenoid is controlled by a side detector finger 58 which extends downwardly in the path of lateral movement of the sheets of paper being registered, the latter of which are guided in their sidewise movement between guides 59 and 60 secured to a frame or housing 61 mounted on a stationary shaft 62. The detector finger 58 is carried by a pivotally mounted bracket 63, which carries an electrical contact 64 adapted to close an electric circuit when passed into engagement with an electrical contact 65 carried by a finger 66, the latter of which is connected to a battery or source of electrical energy 67. Accordingly, it will be appreciated that when a sheet of paper is fed laterally by drop rolls 20 during endwise movement of shaft 17 and said sheet engages the detector finger 58, causing the latter to close the electric circuit at its contacts 64 and 65, the solenoid 56 will be energized for throwing the pawl 52 into engagement with the rack 49 for stopping further endwise movement of the shaft 17, and, therefore, further lateral movement of the sheet of paper, any excess in the throw caused by the cam 33 being absorbed by the spring 46. As soon as the sheet passes progressively forwardly away from the detector finger 58, the detector finger automatically will swing in a manner to break the electric circuit at contacts 64 and 65, causing a de-energization of the solenoid 56, whereupon the spring 57 will draw the pawl 52 out of engagement with the rack 49, and the shaft 17 with the drop rolls 20 will return to normal position under the influence of a spring 68 connected to arm 35 of lever 36.

It will be understood that if the connec-

tions from the cam 33 are changed from the arm 40 to arm 45 of the T-shaped lever for registering the sheet at the opposite side of the press, the pawl 52 will function with the 5 teeth at the opposite end of the rack 49, the pawl 52 then being pivotally mounted in its opposite pivotal support 69, the active end of the pawl 52 being pointed in the opposite direction.

10 It is the intention to cover all modifications of the invention falling within the spirit and scope of the following claims.

We claim:

1. In printing press side registering means, a member for moving a sheet laterally, and means actuated by the sheet for limiting lateral movement of the sheet by electrically controlling movement of said member.

20 2. In printing press side register means, the combination of means for moving a sheet for side registering, a member for limiting movement of said means, and means including an electrical contact element actuated by the sheet, controlling the movement of said member.

30 3. In printing press registering means, the combination of a sheet carrying member movable for registering a sheet, a member for limiting movement of said member, a magnet for operating said stop member, and means responsive to movement of the sheet for controlling the circuit of

said magnet for actuating said stop in accordance with side registering conditions. 35

4. In printing press registering means, the combination of a member for moving a sheet for registering, a rack movable therewith, a pawl for engaging said rack to stop movement of said member, and a magnet responsive to registering movement of the sheet for controlling said pawl to stop the movement of said member.

5. In printing press registering means, a member for moving a sheet for registering, 45 a rack movable with said member, a pawl for limiting movement of said member and said rack, a magnet for actuating said pawl, and a mechanically operated member movable in accordance with registering conditions for electrically controlling the circuit of said magnet.

6. In printing press side registering means, the combination of an endwise movable shaft, a member mounted thereon for moving a sheet for side registering, a rack movable with said shaft, a pawl for stopping movement of said sheet carrying member, a magnet for actuating said pawl, and a mechanically operated member movable 55 in response to side registering conditions for controlling the circuit of said magnet.

Signed at Chicago, Illinois, this 28th day of December, 1921.

JOSEPH R. BLAINE.
CARL HENDERSON.
